US00D722797S

(12) **United States Design Patent**
Plikat et al.

(10) **Patent No.:** **US D722,797 S**
(45) **Date of Patent:** **** Feb. 24, 2015**

(54) **PARTITION AND PARTITION SURFACE**

(71) Applicant: **Herman Miller, Inc.**, Zeeland, MI (US)

(72) Inventors: **Claudia Plikat**, Berlin (DE); **Johann Burkhard Schmitz**, Berlin (DE); **Carola Eva Marianne Zwick**, Berlin (DE); **Roland Rolf Otto Zwick**, Berlin (DE)

(73) Assignee: **Herman Miller, Inc.**, Zeeland, MI (US)

(**) Term: **14 Years**

(21) Appl. No.: **29/480,152**

(22) Filed: **Jan. 23, 2014**

Related U.S. Application Data

(62) Division of application No. 29/453,127, filed on Apr. 25, 2013, now Pat. No. Des. 699,989, which is a division of application No. 29/426,751, filed on Jul. 10, 2012, now Pat. No. Des. 683,159, which is a division of application No. 29/379,704, filed on Nov. 23, 2010, now Pat. No. Des. 665,196.
